MOLD FOR FIBER PULP

Application filed December 12, 1930. Serial No. 501,765.

My invention relates to molds for fiber pulp and the like, and is especially concerned with provisions for venting such molds of air during ingress of the pulp and for ejecting the formed pulp sheets. The invention permits more rapid operation, avoids trouble and inconvenience, minimizes loss due to damaged or defective sheets, and improves the economy of production. Other advantages that can be realized through the invention will appear from my description hereinafter of a selected and preferred form of embodiment.

In the drawings, Fig. I is a fragmentary elevation of a wet machine for forming pulp sheets conveniently embodying my invention, with certain parts in vertical section as indicated by the line and arrows I—I in Fig. II.

Fig. II is a fragmentary elevation at right angles to Fig. I, with certain parts in vertical section as indicated by the line and arrows II—II in Fig. I.

Fig. III is a plan view of the top mold shown in Figs. I and II, with certain associated parts and connections.

Fig. IV shows a vertical section through an air vent shown in Figs. I—III, taken as indicated by the line and arrows IV—IV in Fig. VI.

Fig. V shows a similar section at right angles to Fig. IV with the parts in different relative positions, taken as indicated by the line and arrows V—V in Fig. VI.

Fig. VI is a plan view of the lower portion of the air vent casing, with certain associated parts in section as indicated by the line and arrows VI—VI in Fig. V.

Fig. VII is an inverted plan view of the upper portion of the air vent casing.

Fig. VIII shows a vertical mid-section through the ejector.

In practice, raw fiber sheets for the manufacture of fiber board and the like are formed from aqueous pulp by draining or squeezing away the water, leaving the fibers interlaced in a porous, moist, frail aggregate that can afterward be consolidated or compacted into a board, usually by heat and pressure. One way of forming such a "raw" fiber sheet is 50 by means of a mold of the general type illus-

trated in Figs. I—III, having a shallow, flat cavity into which the pulp is run from hoppers (not shown) through openings 10, 10 in the opposite edges or end deckles 11, 11 of the mold, and whence the water is drained away when the opposite (top and bottom) mold walls 12, 13 are brought together. For this latter purpose, the mold bottom 13 is shown as having a multitude of fine drainage ducts 14, with a perforated or foraminous screen 15 over them. As here shown, the mold top 12 is supported in fixed position by longitudinal beams 16 which are in turn supported by beams 17 mounted on columns 18 alongside the mold. The mold bottom 13 and its supporting structure 19 are shown movable up and down by suitable means, such as hydraulic ram plungers 20. The edge walls or deckles 11 and 21 at the ends and sides of the mold may also be vertically movable, so that they can be lifted out of the way for removal of the formed fiber sheet. Fig. I shows operating rods 22 for the side deckles 21, as well as guides 23 which are mounted on the columns 18.

As shown in Figs. I, II, and III, there are two vents 24, 24 for venting the mold cavity of air when the pulp is entering it, and two ejectors 25, 25 for detaching the formed fiber sheet from the mold top. These devices 24, 24 and 25, 25 are located in the middle third of the mold area, the two devices 24, 24 diagonally opposite one another, and the two devices 25, 25 likewise diagonally opposite one another. From the vents 24, 24 air discharge pipes 26, 26 lead up to a horizontal connection 27, whence a common pipe 28 extends to a suitable point of discharge.

The horizontal pipe 27 also has a water discharge connection 29, for any water or pulp that may rise so high in the air discharge system.

As shown in Figs. IV, V, VI, and VII, each air vent 24 is controlled by a valve plunger 30, so that it can be closed each time after the mold is charged with pulp and opened again after the pulp sheet formed from a charge has been removed or ejected. The valve plunger 30 is arranged to slide in the bore of a casing or cylinder 31 mounted 95 100

in or over an opening in the mold top 12. When in its upper position shown in Fig. V, the valve 30 lies flush with the mold wall and closes the opening therein. Around its inner wall 32, in which the valve 30 slides, the casing 31 affords an annular chamber 33 having an involute or scroll enlargement at its upper end into which opens the corresponding air discharge conduit 26, and also having at its lower end an annular port 34 adapted to communicate with the interior of the valve 30, as hereinafter described. The valve 30 is hollow, with closed ends, and its interior is divided by a septum 35 into lower and upper chambers 36, 37. The lower valve chamber 36 serves primarily for the passage of air from the mold, and the upper valve chamber 37 for the passage of water to wash or flush out pulp that may get into the vent. The lower valve chamber 36 has two annular series of sloping ports 38 and 39 through its wall, both of which are closed when the valve is in its upper closed position shown in Fig. V, and both of which are open when the valve is in its lower position shown in Fig. IV, so that air from the mold can then pass up through ports 38, chamber 36, ports 39 and 34 and chamber 33 to discharge pipe 26.

The valve casing 31 has a water passage 40 connected to a water supply pipe 41 at one end and terminating in a port in the wall of the valve bore at its other end. There is also a water port 42 through the inner casing wall 32, from the valve bore into the small end of the involute of chamber 33. The upper valve chamber 37 has ports 43 and 44 through its wall, that register with the water ports 42 and 40 when the valve is in its upper position shown in Fig. V. This allows the water from the pipe 41 to pass through ports 40 and 44, chamber 37 and ports 43 and 42 into the upper end of chamber 33, where it encounters a curved baffle 45 (Figs. IV and V) that deflects it downward in a circular path, washing out the chamber 33. A valve 46 in pipe 41 serves to control the flow of water. As shown in Fig. I, the valve 46 is urged shut by a helical compression spring 47, but can be opened at will by the operator by means of a pull-rod 48 connected to a bell-crank lever 49 pivoted at 51 and engaging the valve stem 52.

As shown in Figs. IV—VII, the valve casing or cylinder 31 is made in upper and lower halves 56 and 57, divided in the mid region of the scroll chamber, the entire inner wall 32, however, belonging to the upper half. There is also a separate lower member 58, closing the bottom of the lower casing half 57 and forming a continuation of the valve bore in the upper half 56, and having a flange that fits into the top mold opening. The upper end of the valve 30 is closed by a plug 59 screwed thereinto, and to this plug the

vent-operating rod 60 is attached. A clean-out plug 61 is shown in line with the water port 40. A dowel pin 62 fixed in one of the casing halves 56, 57 facilitates assembling them properly. The casing 31 is secured to the mold top 12 by screws 63 extending up through the mold top and taking into threaded holes in an external flange on the lower casing part 57. These screws 63 also extend (loose) through holes in an external flange 75 on the casing part 56.

As shown in Fig. VIII, each ejector 25 has a movable plunger 65 adapted to lie flush with the lower face of the top mold 12 and close the opening therein while the mold is being charged and the sheet formed, and to be thereafter projected downward to push the formed sheet away from the mold top, and also has means for admitting or forcing fluid between the mold top and the formed sheet, to separate them and break the vacuum that may otherwise exist between them when initially separated. In the present instance, the fluid admitting valve means is combined with the pusher plunger or depressor 65, consisting of a hollow valve with closed ends, arranged to slide in the bore of a casing or cylinder 66 mounted in or over an opening in the mold top 12. The plunger 65 has an annular series of outward sloping ports 67 at its lower end, which open through its periphery and are closed when it is in its uppermost position, but are just fully exposed when it is slightly depressed as shown in Fig. VIII, so as to blow air or other fluid into the space opened by the downward push of the member 65. Fluid for this purpose is admitted or supplied to the interior of the valve 65 through an annular series of upward sloping ports 68 which open through the periphery of the valve and are shown in Fig. VIII just fully open into an internal annular groove 69 in the casing 66, to which a fluid supply pipe 70 is connected. As shown, the upper end of the casing 66 has a bleed vent 71, for the escape of any fluid that may leak up around the cylinder 65. The upper end of the cylinder 65 is closed by a plug 72 screwed thereinto, to which the ejector-operating rod 73 is attached. The casing 66 is shown as including a separate lower member 74 very similar to the part 58 in function and conformation, and as secured by screws 75 just as the casing 31 is secured.

The lower parts 58 and 74 of the casings 31 and 66 may be of bronze or other suitable material, bored with special care to seal fluid tight (but without binding) around the valves 30 and 65, respectively.

As shown in Figs. I and II, the vent and ejector-operating rods 60, 60 and 73, 73 extend up to actuating cams 76, 76 and 77, 77 fast on horizontal shafts 78, 78 and 79, 79 mounted in bearings on the beams 17. The cams 76, 76 are operated by connecting rods 130

80, 80 connected to crank arms 81, 81 fast on a common shaft 82, which may be operated by a crank arm 83 fast on said shaft 82 and a rod 84 connected to said crank arm 83. 5 The cams 77, 77 are operated by similar connections 85, 86, 87, 88, 89. Each of the rods 60 and 73 is yieldingly urged upward by helical compression springs 90 acting between a disc or spider 91 fast on the rod and 10 a fixed supporting structure 92 spanned between adjacent beams 16. The springs 90 are mounted around rods 93 whose lower ends are secured to the structure 92 and whose upper ends are attached to a disc or spider 94 through which the rod 60 or 73 can slide freely. Upward movement of each rod 60 and 73 is limited by a boss on its disc 91 engaging the disc 94; downward movement of the rod is limited by its disc 91 engaging a 15 boss on the structure 92. The upper end of each rod 60 and 73 is provided with a contact roller 95 for its cam 76 or 77, and is guided by a bracket 96 attached to one of the beams 17. Helical tension springs 97 act to 20 pull the rods 80, 85 to the right (Fig. I), and to rotate the cams 76, 77 clockwise as far as permitted by stops 98.

In practice, assuming the mold ready for a 30 charge of pulp, as shown in Fig. I, a cycle of operation may be as follows:

The rod 84 is pulled down as far as possible, turning the cams 76 counter-clockwise one revolution and depressing the rod 60, thereby 35 opening the valves 30 to vent the mold of air, but closing the water ports 43, 44,—all as shown in Fig. V. As the valve 30 opens its ports 39, 38 from the chamber 33 into the mold, all pulp and wash water from the preceding cycle of operations runs into the 40 mold and drops to its bottom 13,—whose drainage ducts 14 are at this time shut off from discharge. Pulp is admitted to the mold in the usual manner, the valves 30 meanwhile remaining open. The pulp fills the 45 mold from both ends, while the air is exhausted from between the incoming pulp streams through the valve 30, as already described; and some of the pulp even follows the air up into the vent chamber 33.

50 The operating rod 84 is now released, and the cams 76 are thereupon returned clockwise by the springs 97 back to the position shown in Fig. I, and the valves 30 are raised and closed by their springs 90, shutting off the 55 vents 24, 24 from the mold as shown in Fig. V, but opening the water ports 43, 44, so that water can enter and flush the chamber 33. This flushing may occur automatically, if the supply control valve is left open all the 60 time, and continue as long as the valve 30 remains closed; or it may be only momentary, as determined by the opening of the water control valve 46 by the operator.

65 The valve 30 being closed, the ducts 14 are opened to drainage and the mold walls 12, 13

brought together, by operation of the plungers 20, squeezing and draining off the water and leaving the fibers interlaced or matted together in a moist, coherent raw sheet S, as shown in Fig. V. Thereupon the mold walls 12, 13 may be separated, and the deckles 11, 21 70 raised out of the way, to permit removal of the formed fiber sheet S.

For this purpose, the operating rod 89 is pulled down as far as possible, turning the cams 77 counter-clockwise one revolution and depressing the rod 73, thereby also depressing the ejector valve 65 as shown in Fig. VIII and admitting the air between the sheet S and the top mold 12, which is thus detached from the top mold and drops on the mold bottom 13, whence it is removed. As the sheet S drops, the rod 89 is released, the cams 77 are returned clockwise by the springs 97 back to their position shown in Fig. I, and the valves 80 85 65 are raised and closed by their springs 90.

It only remains, therefore, to return the walls 12, 13 and the deckles 11, 21 to their positions of Fig. I, whereupon the apparatus 90 is ready for another cycle of operation.

Having thus described my invention, I claim.

1. The combination with the mold of a hydraulic wet machine, of means for venting the mold cavity of air through the top of the 95 mold while the mold is being filled with pulp, and means for subsequently pushing the pulp sheet thus formed away from the mold top and admitting air between them.

2. The combination with a hydraulic wet 100 machine mold and its top wall, of air vent means on the mold top for venting the mold cavity of air while it is being filled with pulp, ejector means on the mold top for detaching the pulp sheet thus formed from the mold top, means for actuating the ejector means, and means for actuating the air vent means.

3. The combination with the mold of a 105 hydraulic wet machine, of means for venting the mold cavity of air through the top plate of the mold while the mold is being filled with pulp.

4. The combination with the mold of a 110 hydraulic wet machine, of a valve on the top of the mold for venting the mold cavity of air while it is being filled with pulp, and means for flushing the valve of pulp entering it after the air.

5. The combination with the mold of a 115 hydraulic wet machine, of a valve casing on the top of the mold having air ports and passages in communication with an air vent and water ports in communication with a water supply, and valve means in said casing controlling communication of the air 120 ports with the mold cavity and also controlling communication of the water ports with the air passages.

6. The combination with the mold of a 125 hydraulic wet machine, of a valve casing on 130

the top of the mold having air ports and passages in communication with an air vent and water ports in communication with a water supply, and valve means reciprocable in said 6 casing having separated water and air spaces in its upper and lower ends, and adapted when raised to cut off its air space from the mold cavity and from the water supply while admitting water to the air passages of the 10 casing, and when lowered to connect its air space and said air passages with the mold cavity.

7. The combination with the mold of a 15 hydraulic wet machine, of a valve casing on the top of the mold with valve bore open into the mold cavity at its lower end, air vent ports and passages in said casing opening into said bore, water supply ports opening into said bore above said air vent ports and 20 from said bore into said air vent passages at an intermediate level, and valve means in said bore for connecting the mold cavity with said air vent ports when the water ports are closed and for interconnecting the water 25 ports when the air vent ports are closed.

8. The combination with the mold of a 30 sheet-forming hydraulic wet machine, of an ejector for pulp sheets formed therein comprising means for pushing a sheet away from the mold wall and means for admitting fluid under pressure between the sheet and the mold wall.

9. The combination with the mold of a 35 sheet-forming hydraulic wet machine, of an ejector for pulp sheets formed therein comprising a push device in the midst of the mold top for depressing a sheet away from it, and means for admitting fluid under pressure into the space thus opened between the mold top 40 and the sheet.

10. The combination with an apertured 45 mold wall of a hydraulic wet machine, of an ejector for pulp sheets formed in the machine comprising a closure for the opening in the mold wall projectable therefrom to push a sheet away around the opening, and means for forcing fluid through the opening into the space between the sheet and the mold top.

11. The combination with an apertured 50 mold top of a hydraulic wet machine, of an ejector for pulp sheets formed in the machine comprising a cylinder extending upward from said opening; a hollow plunger in said cylinder adapted to close the opening 55 when raised, but compressible to push a sheet away from the mold top around the opening, and apertured for the discharge of fluid from its interior downward and outward into the space between the depressed sheet and the mold top; and means for supplying fluid under pressure to the interior of said plunger.

In testimony whereof, I have hereunto signed my name at Trenton, New Jersey, this 9th day of December, 1930.

FRANCIS S. FARLEY.
